UNITED STATES PATENT OFFICE.

WILLIAM H. BAKER, OF WINDING GULF, WEST VIRGINIA.

HINGE.

Application filed July 22, 1925. Serial No. 45,400.

The invention relates to hinges of the type that cause doors with which they are associated to close after they have been opened.

5 Hinges made in accordance with this invention are adapted particularly for use with heavy wood-and-metal freely-swinging doors such as used in mines across passages and in other places, and the hinges are so formed 10 and arranged that the doors may be opened when an engine or car pushes thereagainst and will close by gravitational action when the last car of a series has passed.

When considered with the description 15 herein, the characteristics of the invention are apparent from the accompanying drawings, forming part hereof, wherein an embodiment of the invention in association with a pair of mine-doors is disclosed, for purposes of illustration.

Like reference-characters refer to corresponding parts in the views of the drawings, of which—

Fig. 1 is a view, in elevation, of the hinges 25 in association with mine-doors;

Fig. 2 is a side elevation of the base plate;

Fig. 3 is an end elevation thereof;

Fig. 4 is a plan view thereof;

30 Fig. 5 is a section on the line 5—5, Fig. 4;

Fig. 6 is a side elevation of the pintle-end portion of one of the swingable members;

Fig. 7 is a view on the line 7—7, Fig. 6.

Having more particular reference to the 35 drawings, A designates a sill extending across a mine passage or doorway, B posts extending upwardly therefrom at each side, C an upper transverse member on the posts positioned directly above the sill, D doors 40 closing the passage, and E sheet-metal coverings on the sides of the doors at places against which engines, cars, and other vehicles contact while going through the passage.

45 Upper right-angle plates 8 of the hinge are sunk into the posts and the upper transverse members at the corners formed thereby, and they are secured in place by bolts 9 in the posts and lag-screws 10 extending into 50 the transverse member, the plates being formed with countersunk holes 11 to accommodate the shanks and heads of the fastenings. The upper or horizontal portion of each of these plates has a substantially 55 vertical pintle-socket 12.

Right-angle base plates 13 are positioned

directly below the upper plates, they are like the upper plates except as hereinafter described, and they are held in place at the corners formed by the sill and post in a 60 manner similar to the upper plates.

The horizontal portions of the base plates, which rest on the sill, have pintle-sockets 14, which are located nearer to the posts than the pintle-sockets 12 of the upper plates, 65 and substantially midway between the sides.

The horizontal portion of each base plate is characterized by a depression in its upper face extending from side to side thereof between its ends, and the pintle-socket is located at the end thereof nearer the post. The bottom of the depression is a longitudinal groove 15, which is round in cross section, and which extends longitudinally from the socket to the other end of the depression. Surfaces 16 of the depression slope laterally and upwardly from each side of the groove and socket, whereby the depression is substantially V-shape in cross section 70 on each side of the groove and socket. 75 Surfaces 17 slope downwardly from the socket end to the other end, whereby there are afforded apex lines 18, which converge from the sides of the plate to the sides of the groove at its end. The result of provision of these sloping surfaces 17 at the sides is that the surfaces 16 sloping to the groove are substantially triangular in plan with their bases or wider portions at the socket end, and the sloping surfaces 16 and 80 17 are divided by the more or less theoretical apex lines 18. The surfaces at the apex lines and the sloping surfaces 16 cooperate with swingable hinge members to cause a door to close.

Each of the swingable hinge members 85 comprises an elongated portion or strap 19, which is secured to a side of a door, and an end portion 20 turned substantially at right angles to the strap. The end portions 20 90 have rounded ends 21, which are substantially horizontal when the members are in place on a door, and a pintle 22 extends from the outer sides of these ends into the pintle-sockets of the upper and base plates. So 95 far as concerns the upper swingable hinge members, it is immaterial whether or not they have rounded ends capable of cooperating with the surfaces of the base plates hereinbefore described, but it is preferable 100 to make all those members substantially the same, so that they may be interchangeable.

2 While the doors are in closed position, the rounded ends of the lower swingable members rest in the grooves 15 of the base plates, and thereby the doors are held closed. When 5 a door is opened, the rounded end of the hinge member moving against a rounded surface of the groove and against a sloping surface 16 and along an apex line 18 slightly raises the door; and, when the door is re- 10 leased, the weight thereof imposed by the lower end of the swingable hinge member on the inclined surfaces of the base plate causes the door automatically to close. Mine-doors for which this hinge particularly 15 is intended are heavy, and their weight is sufficient to cause the hinge to act as described.

As the sloping surfaces of the base plates extend to the sides thereof, the lower ends 20 of the swingable hinge members bear against those surfaces even when the doors are entirely open, and thus the doors close automatically from the full-open position, which would not be the case if the lower ends 25 reached and rested on a substantially horizontal surface at open position.

Theoretically it is necessary to provide for closing a door only from an angle of 90 degrees with respect to the closed position. 30 As a matter of fact, however, in the case of mine-doors, engines and cars bump against them, and the doors sometimes swing slightly beyond the 90-degree position. It has been found in practice, with hinge arrangements 35 such as disclosed herein, that the doors will close automatically from such extreme positions.

Having thus described my invention, what

I claim as new, and desire to secure by Letters Patent, is—

40 1. A hinge comprising a base plate having a depression extending from side to side thereof, a pintle-socket in said depression, and a groove extending from said socket at the base of said depression, the surface of 45 said depression sloping upwardly and laterally from each side of said groove and downwardly from said socket toward the other end, a swingable member having a rounded end arranged to seat in said groove and to 50 swing in contact with either of said laterally-sloping surfaces, and a pintle on said member adapted to seat in said socket.

55 2. A hinge comprising a base plate having its body downwardly cut away and formed with a depression extending at one of its ends entirely thereacross, a pintle-socket in the other end portion of said depression, and a groove extending longitudinally from said socket at the base of said depression, there 60 being plane surfaces in said plate sloping laterally and upwardly from each side of said groove and socket whereby said depression is substantially V-shape in cross section adjacent to its median line, and there 65 also being other plane surfaces in said plate extending to the sides thereof from said first-mentioned surfaces and sloping downwardly from the socket end to the other end of the plate; and a swingable member having a rounded end arranged to seat in said groove and to swing in contact with either of said laterally-sloping surfaces and a pintle adapted to seat in said socket.

In testimony whereof I affix my signature.
WILLIAM H. BAKER.
